UNITED STATES PATENT OFFICE.

THOMAS HYDE, OF ALBANY, NEW YORK.

HOUSE-VENTILATING SYSTEM.

SPECIFICATION forming part of Letters Patent No. 606,417, dated June 28, 1898.

Application filed June 26, 1897. Serial No. 642,395. (No model.)

To all whom it may concern:

Be it known that I, THOMAS HYDE, a citizen of the United States, residing in the city and county of Albany, State of New York, 5 have invented a new and useful House-Ventilating System, of which the following is a specification.

My invention relates to systems for ventilating the apartments of a building by means 10 of the pipes leading from the washbowls, bathtubs, closets, and other connections with the drain, causing a circulation from the room in which the washbowls, closets, &c., are placed through the pipes connected with said washbowls, closets, &c.; and the object of my invention is to provide a ventilating system which shall not only prevent the escape of gases from the drains and sewers into the apartment within which a washbowl, bathtub, or closet is placed, but which will also cause the escape of foul air from said apartments through the pipes connected with the drain. I attain this object by means of the mechanism illustrated in the accompanying 25 drawings, in which—

Figure 1 is a section of a building, showing the connections of the pipes with various washbowls, sinks, bathtubs, and closets placed within apartments in a house and one 30 method of connecting up the same to cause a circulation of air from the apartments to the exterior of the house. Fig. 2 is a section of a trap, and Fig. 3 is a section of a valve.

Similar letters refer to similar parts throughout the several views.

It is a well-known fact that much inconvenience and many dangerous diseases result from the poisonous gases escaping from sewers and drain-pipes into the living-rooms of dwellings and other buildings, and in endeavoring to avoid these deleterious results many devices have been produced in which improved traps are employed to accomplish the 45 desired result in the building. There is a danger, however, that the most perfect trap may become emptied of its sealing-water because of a partial vacuum occurring in the drain or sewer or because of evaporation of the same, leakage, or other defects, allowing 50 the gases to escape through the trap into the

house, to the great danger of its inhabitants. In my ventilating system I provide a means by which I may do away with the trap entirely and cause a circulation of the air positively 55 downward through the fixtures in the apartment connected with the drain and carry through the drain fresh air from the outside of the house, preventing the possibility of the escape of gases from the sewer or drain into 60 the apartments of the building.

In the drawings, A represents a drain-pipe within a building B, which is preferably trapped at C from the drain D and provided with a valve J, to which is connected a fresh- 65 air-carrying pipe E, having an opening e outside of the building. I also connect the drain A with a pipe a, which extends upward through a chimney F, preferably extending to the top of the chimney, allowing for the circulation 70 of fresh air from the inlet e through the drain-pipe A through the outlet a within the chimney F, as indicated by arrows in Fig. 1.

G represents a washbowl connected with the drain A by the pipe g. I also connect the 75 pipe g with the pipe H, which passes into the chimney F and preferably extends to the top of the chimney. Within the pipe g and between the drain and the pipe H, as at h, I preferably place a valve J, said valve provided with a valve-disk j, pivoted at one end, as at j', within the valve-casing and having at the end near the pivot a weight k, tending to hold the valve closed. The valve-disk j is adapted to open in one direction only, as 85 shown by dotted lines in Fig. 3, it being prevented from opening in the opposite direction by means of the stop k'. As placed in position within the pipe g the valve opens downward, allowing for the escape of the contents 90 of the pipe g into the drain A, but preventing the passage of the contents of the pipe A into the pipe g.

I do not limit myself to the use of a valve within the pipe g, since it is placed there to 95 individualize each portion of the system. The trap K (shown in Fig. 2) may be substituted for the valve J, or a different trap or different valve may be placed therein, or valve and trap may both be omitted.

L represents a bath-tub, with its pipe l connected with the drain A and provided with a

pipe L', extending into the chimney F, and at l' with a valve J.

M represents a closet connected with the drain by the pipe m and having a pipe M' extending into the chimney and the valve J placed between the pipe M' and the drain A.

N represents a sink, with its pipe n connected with the drain A, the pipe N' connected therewith and extending into the chimney F, the valve J placed in said pipe n.

O represents stationary tubs connected with the pipe o, leading to the drain A, and the pipe O', extending into the chimney F, the pipe o provided with the valve J.

P represents a closet, having a pipe p connected with the drain A, provided with a valve J and connected with the pipe P', leading into the chimney F.

In each of these fixtures there is a pipe extending into the chimney connected with the discharge-pipe from the fixture between the fixture and the drain-pipe. The pipes in the chimney F extend to the top of the chimney preferably, thus communicating with the exterior of the house. A draft is thus maintained through the pipes in the chimney, causing a suction upon the pipes connected with the fixtures, occasioning the withdrawal of air from the apartments within which the fixtures are located.

When there is a fire within the range or other apparatus (not shown in the drawings) connected with the chimney, there will be caused a rarefaction of the air within the pipes in the chimney, which will accelerate the current of air through the pipes and assist in the ventilation of the rooms; but under any circumstance, whether there is a fire connected with the chimney or not, there will be a circulation of air from the apartments through the pipes in the chimney. I therefore do not limit myself to the use of a chimney connected with stoves or other heating

apparatus, as any flue would answer all purposes.

I am aware that heretofore a fresh-air pipe placed outside of a building was connected with the drain within the structure, having for its object the introduction of fresh air into the drain within the house.

I am also aware that heretofore the discharge-pipes from water-closets and urinals have been connected with a flue; but in all of the devices heretofore used and all systems heretofore employed with which I am familiar there has been no provision made for passing fresh air through the drain into the house, carrying the same directly from the drain through a pipe in a flue, nor have any of the devices or systems with which I am familiar provided for connecting the discharge-pipes from the closets and other fixtures with pipes in a flue in such a manner that traps may be omitted and the escape of gas prevented from the drains.

What I claim as my invention, and desire to secure by Letters Patent, is—

A system for ventilating apartments in a building, consisting of a drain, a fresh-air inlet connected therewith, an air-escape pipe connected with said drain, a chimney through which said air-escape pipe extends, the discharge-pipes from the plumbing-fixtures in said building connected with said drain, pipes located in said chimney connecting respectively with said discharge-pipes, in each of said discharge-pipes, between the drain and the pipes connected with said discharge-pipes extending into said flue, a means for preventing passage of air or gas from the drain through the discharge-pipes, substantially as described.

THOMAS HYDE.
